ATTORNEY

WITNESS:

UNITED STATES PATENT OFFICE.

DANIEL R. SCHOONOVER, OF TUXEDO, NEW YORK.

CLOTHESLINE TIGETENER.

Application filed October 13, 1922. Serial No. 594,325.

To all whom it may concern:

Be it known that I, DANIEL R. SCHOONOVER, a citizen of the United States, residing at Tuxedo, in the county of Orange and State of New York, have invented new and useful Improvements in Clothesline Tighteners, of which the following is a specification.

My present invention has reference to a means for tightening a clothes line, and has for its object to produce an article of this character which can be stamped from a sheet of metal so that the same can be cheaply manufactured and marketed, and which will perform its functions in an easy, expeditious and accurate manner.

A further object is to produce a clothes line tightener comprising a body member having fingers adjacent one end around which the line is twisted when the body member is turned, means at its other end for engaging the line to prevent the untwisting thereof, means on one of the line engaging elements for supporting a clothes pin bag or the like, means at its other end for facilitating the manipulation of the device, and also providing a means whereby the device may be suspended from a support when not in use.

The drawing which accompanies and forms part of this application, illustrates a satisfactory embodiment of the improvement reduced to practice, and wherein:—

Figure 1 is a side elevation illustrating the device in use.

Figure 2 is a perspective view of the improvement.

As disclosed by the drawing, the improvement is constructed from a single sheet of metal stamped or cut to provide an elongated body portion 1 which has one of its edges, adjacent to one of its ends provided with laterally extending spaced fingers 2 and 3 respectively. Each finger, adjacent to its outer end is provided with an out-

wardly directed foot extension 4 and 5 respectively, the finger 2, below the foot 4 being formed with a ring portion 6. As disclosed in Figure 1 of the drawing, the clothes line is first inserted between the fingers 2 and 3 and the body 1 is turned to wind the clothes line around the fingers. The foot portions 4 and 5 prevent the coiled portion of the clothes line being moved off of the fingers.

At its opposite end, the body 1 has its edge provided with the fingers 2 and 3 formed with an extension which is bent upon itself to provide a substantially U-shaped tongue 7, and this tongue is designed to receive therein one of the taut leads of the clothes line 8. The body 1, on its edge opposite that provided with the tongue 7 is formed with a ring extension 9, the same serving as a finger hold for manipulating the device in tightening the clothes line, and also serving as a means whereby to engage a hook or nail so that the device can be suspended at a convenient place when not in use. The eye 6 serves as a suspending mean for articles used by the laundress, as for instance, the same may suspend therefrom a bag containing the clothes pins.

Having described the invention, I claim:—

As an article of manufacture, a clothes line tightener stamped from a sheet of metal to include an elongated body having one of its edges adjacent one of its ends formed with spaced laterally extending fingers that terminate in outwardly directed feet, one of said fingers outward of the foot thereon being formed with an eye, said body having its said edge, adjacent its opposite end formed with a laterally arranged substantially U-shaped tongue and its opposite edge formed with an eye extension, all as and for the purpose set forth.

In testimony whereof I affix my signature.

DANIEL R. SCHOONOVER.
